UNITED STATES PATENT OFFICE.

JAMES ERNEST TATHAM, OF LONDON, ENGLAND, ASSIGNOR TO THE INTENSIFIED GAS LIGHT COMPANY, LIMITED, OF SAME PLACE.

GAS-BURNER.

SPECIFICATION forming part of Letters Patent No. 655,527, dated August 7, 1900.

Application filed December 19, 1899. Serial No. 740,911. (No model.)

To all whom it may concern:

Be it known that I, JAMES ERNEST TATHAM, gas engineer, a subject of the Queen of Great Britain and Ireland, and a resident of 12 Fawcett's Holme road, Kensington, London, England, have invented certain new and useful Improvements in or Connected with Gas-Burners, (for which an application has been made for a British patent, No. 14,023, dated July 7, 1899,) which invention is fully set forth in the following specification.

This invention relates to gas-burners used in what is known as "incandescent gas-lighting"—that is to say, burners in which the gas passing to the place of ignition draws in air with it, the mixture of gas and air burning and rendering incandescent a hood or mantle. In such burners as hitherto made I have found that if the pressure be less than one inch owing to the power of the gas to draw in air not being utilized efficiently the said burners do not operate efficiently, the incomplete mixture of the air and gas rendering the combustion of the mixture imperfect.

It is the object of my invention to overcome this objection and to provide means whereby with a minimum consumption of gas and with gas at a pressure varying from half an inch to an inch a flame of such a temperature is produced as to give a greatly-improved lighting effect relatively to the amount of gas consumed. I have found by numerous experiments and careful trials that in order to effect this it is necessary to provide a particular upward angling of the air-inlets surrounding a gas-inlet nozzle whose exterior is made of the same upward angle as that of the air-inlets and to make the opening from the said nozzle in a plane at a certain regulated distance above the plane in which the upper sides of the air-inlets are located, all as hereinafter explained.

I will describe the invention with reference to the accompanying drawings.

Figure 1 is an elevation, Fig. 2 a vertical section, and Fig. 3 a transverse section, on the line 1 2, Fig. 4, of so much of a burner as is necessary to illustrate my invention. Fig. 4 is a view like Fig. 1, but with a chim-

ney, Fig. 1 showing the burner for use without a chimney.

a is the gas-inlet, terminating in a nozzle *a*², situated in a mixing-chamber *b*, into which open the air-ports *b*², in which chamber the gas and air become mixed and pass upward through the conical pipe *c* and straight pipe *d* to the gauze *e* at top, at which the mixture of gas and air is ignited and burns to render incandescent the hood or mantle *f*, which is supported in any usual or suitable way—for example, by a forked rod *f*², projecting axially through the gauze *e*, as shown, or by a rod secured to the exterior of the burner and projecting in the form of a hook above the center of the gauze *e*. The air-ports *b*² are made in such a manner as to have an upward direction, as shown clearly in Fig. 2, the angle of the said air-ports *b*² being the same, or about the same, as the angle of the exterior of the gas-nozzle *a*². In practice I have found that an angle for the said air-ports *b*² of or about thirty degrees to the axis of the burner gives the best results and that the vertical distance of the opening of the nozzle *a*² above the upper side of the air-ports *b*² should be one-quarter of an inch or thereabout. The tube *d* is shown as being arranged on the conical tube *c*, so that it can be raised and lowered on the said tube *c* and be fixed in position by a set-screw *d*². The height of the nozzle *a*² can also be regulated by screwing it out from or into the mixing-chamber *b* and fixing it in position by a set-screw. At *g* I have shown "hit-and-miss" air-openings, which can be regulated by rotating the upper part of the said chamber upon the lower part. *g*² is a set-screw for fixing the parts in their adjusted position, the said screw screwing through a hole in the outer part and engaging with a groove *g*³ in the inner part, so holding the parts in place upon each other. I may omit the air-openings *g*; but it is generally convenient to provide them, as they can be completely closed when the gas is of ordinary quality, and they will be useful to supply additional air in the event of the burners being used with a supply of gas above normal richness.

Having now particularly described and as-

certained the nature of this invention and in what manner the same is to be performed, I declare that what I claim is—

A gas-burner consisting of the combination 5 of a mixing-chamber into which projects a nozzle from the gas-inlet and into which open upwardly-directed unobstructed air-inlets surrounding the said nozzle and from which mixing-chamber project upward first a conical and then a straight pipe surmounted by 10 a mantle the said air-inlets being made at an angle substantially the same as that of the exterior of the said nozzle the said angle be-

ing thirty degrees or thereabout to the axis of the burner and the opening of the said 15 nozzle being one-quarter of an inch or thereabout above the upper side of the air-inlets all substantially as hereinbefore described.

In testimony whereof I have signed this specification in the presence of two subscribing witnesses.

JAMES ERNEST TATHAM.
